E. H. DRYER

CHECK PROTECTOR

Filed Dec. 28, 1921

Fig. 1.

Fig. 4.

INVENTOR,
Edwin H. Dryer;
BY
Raymond Lee Blakeslee,
ATTORNEY.

UNITED STATES PATENT OFFICE.

EDWIN H. DRYER, OF BAKERSFIELD, CALIFORNIA.

CHECK PROTECTOR.

Application filed December 28, 1921. Serial No. 525,283.

To all whom it may concern:

Be it known that I, EDWIN H. DRYER, a citizen of the United States, residing at Bakersfield, in the county of Kern and State of California, have invented new and useful Improvements in Check Protectors, of which the following is a specification.

- This invention relates to check protectors, and particularly to a check protector adapted to hold a check book, and from which check book a check may be removed and perforated by suitable means, the check being perforated to prevent a raising of said check above the amount indicated on said check.
- 10 The invention contemplates the provision of means whereby the check protector may be easily carried in the pocket of its user, and which incorporates a construction that is not bulky and is easy to use.
- 15 The invention has for an object the provision of an improved check protector which is simple and inexpensive in construction, of great utility, durability and efficiency for the purpose intended.
- 20 In practicing the invention I provide a suitable casing which is formed so as to have two compartments, one of which may carry the check book in its entirety, and the other of which may receive a check detached from
- 25 said check book and which check is to be perforated to prevent a raising of the amount of the check.

With the above objects in view, the invention consists in the novel and useful provision, formation, construction, combination, association and inter-relation of parts, members and features, as illustrated in some of its embodiments in the accompanying drawing, described in the following detailed statement and finally pointed out in claims.

In the drawing:

Figure 1 is a top plan view of the check protector in its entirety;

Figure 2 is a longitudinal sectional view of the protector shown in Figure 1 and taken on the line 2—2 of said figure, and looking in the direction of the appended arrows;

Figure 3 is a transverse sectional view of the device shown in Figure 1, and taken on the line 3—3 of said figure, and looking in the direction of the appended arrows, the dotted lines in said figure indicating the relative separation of the casing at its hinge point;

Figure 4 is a fragmentary cross sectional view of the means for perforating the check;

Figure 5 is a fragmentary cross sectional view of certain of the means used for perforating the check to indicate certain amounts;

Figure 6 is a face view of one of the perforating elements;

Figure 7 is a fragmentary view, certain parts being in section, of perforating means; and

Figure 8 is a fragmentary detail of the hinge connection of said casing.

Corresponding parts in all the figures are designated by the same reference characters.

Referring with particularity to the drawing, A designates the improved check protector in its entirety, and of which a is the casing, and b perforating elements for indicating various amounts. The casing a is made in two parts, as 1 and 2, with the said parts hingedly connected together, as at 3. The part 1 includes a top wall member 4 and a partition wall 5 held in spaced relation and respectively provided with downwardly directed ends 6, 7, 8 and 9. The ends 6 and 7 terminate in knuckles 10 and 10^a. The bottom member 2 likewise has its edges angularly directed, as shown at 11 and 12 with the part 12 provided with knuckles 13. A pin 14 extends through the knuckles 10 and 10^a and 13, and holds the parts 1 and 2 in hinged relation. The wall member 4 is provided with slots 15, 16, 17 and 18, the slot 17 inter-connecting the slots 15 and 16. These slots act as guide-ways for the various perforating elements b, which perforating elements b include a head member 19 carrying suitable indicia 20, and which head carries a shank 21 adapted to extend through the slots with a small washer or plate member 22 carried on one surface of the member 4 and a second plate member 23 joined with said shank on the opposite side of the member 4. A coil spring 24 surrounds the shank 21 and bears against the head and the washer 22. The plate 23 carries projecting prongs 25 which are arranged to represent a figure or letter, that in Figure 5 representing the numeral 2 and the prongs 25 would be so spaced and arranged on the plate 23 as to perforate an object and form the numeral 2 therein when the head 19 is depressed. A plurality of the means b is of course provided so as to give a large range of figures

and amounts so that a check may be perforated for any amount. I also provide other perforating elements such as shown at *c*, *d* and *e*. The perforating elements *c* and *d* are preferably formed of letters, the words "Not over" being indicated at *d*, and the word "Dollars" indicated at *c*.

The construction, however, of the perforating elements *c* and *d* are slightly different from *b* in that the perforating elements directly engage a sheet of paper when the casing is closed, perforating the same, and not requiring the depressing of a head, such as is true of the perforating elements *b*.

10 This remark likewise applies to the perforating elements *e*, which may be a monogram or the name of a firm. The perforating elements *c*, *d* and *e* are so arranged that the perforating prongs of the same, as 26,

20 27 and 28 will not be injured when the casing is closed, as indicated in Figures 2 and 3. This is readily accomplished by depressing portions of the members 5 to form small

25 pans 29 and 30 directly beneath the elements *c*, *d* and *e*, each of which pans carries a soft rubber pad 31 and 32, so that when the casing is closed the prong elements 26, 27 and 28 will press into the rubber pad and prevent injury thereto. The perforating ele-

30 ment *c* is allowed a slight movement within the slot 18, so that several of the elements *b* may be received between the elements *c* and *d*, as best illustrated in Figure 1. A check book 33 may be carried within the bottom

35 member 2 and held in position at one end as by means of a spring member 34. It will of course be understood that a check book will be prevented from loss from the casing *a* when the casing is closed, as the member 5 and the member 2 cooperate. The angularly directed end 9 of the part 5 carries a

40 clip member 35 which has two wing portions 36 and 37 adapted to engage the parts 1 and 2 of the casing *a*, and to hold the said casing normally closed. A bending back of

45 the wings 36 and 37 will of course release the parts 1 and 2 so that they may be swung open, as indicated by the dotted lines in Figure 3 about the hinge point 3.

50 In operation the perforating means *b* may be slid along the guide-ways or slots 15 and 16 past the slot 17, until the desired perforating member is reached. Take for instance the numerals 65, referring to Figure 1, the perforating element *b* indicating 60

would be moved up the slot 17 and say into the slot 16. The two perforating elements *b* carrying the numbers 1 and 55 would be slid along the slot 16 past the slot 17, and 65 the perforating element *b* carrying the numerals 65 would be moved along the slot 16 until it reached the slot 17, whereupon it would be slid along said slot 17 until it occupied the position formerly occupied by

65 the perforating elements carrying the nu-

merals 60. If the member 4 were now revolved about its hinge connection and a check placed upon the member 5 and the member 4 then closed in the position illustrated in Figure 3, the perforating elements 70 *c*, *d* and *e* would perforate the check and upon depressing the perforating element *b* the check would be perforated indicating sixty-five dollars.

There is a small amount of play allowed 75 each of the perforating elements *b*, as shown in the figures, and the spring element 24 carried by each of the elements *b* tends to keep each element in position ready for depression at any time. As stated, the element 80 *c* may be slid backward and forward so as to accommodate different amounts between the elements *c* and *d*.

It is obvious that many changes and variations and modifications may be made in departure from the particular description and showing of the accompanying drawing, in adapting the invention to varying conditions and requirements of use and service, without departing from the true spirit of the invention. 85

Having thus disclosed my invention, I claim and desire to secure by Letters Patent:

1. A check protector, including a two-part casing, one of which is adapted to carry a check book and the other of which is adapted to receive a check to be perforated; there being means mounted on the casing for perforating said check. 95

2. A check protector, including a hinged casing and a dividing wall within the same; said wall dividing the casing into two parts, one part being adapted to receive a check book and the other being adapted to receive 105 a check to be perforated, and means mounted on the casing for perforating the check; said means including depressible members and extending in part exteriorly of the casing. 110

3. A check protector, including a hinged casing, and means for locking said casing, said casing having top and bottom walls, the top wall having slots formed therein and perforating elements carried by the top 115 wall and received within the slots; said perforating elements being so formed as to permit individual manipulation thereof and means with which said perforating elements cooperate to perforate a check. 120

4. A check protector, including a casing having side, end, top and base members; there being a dividing wall within said casing; said dividing wall, top and base members being hingedly joined, means carried 125 by the dividing wall for locking the casing together and means mounted on said casing for perforating a check.

5. A check protector, including a casing having side, end, top and base members; 130

- there being a dividing wall within said casing; said dividing wall, top and base members being hingedly joined, and means carried by the dividing wall for locking the casing together; said dividing wall being formed with depressed portions, perforating elements carried by one member of the casing, and means within the depressed portions of the dividing wall for protecting the perforating elements when the casing is closed. 6. A check protector, including a hinged casing, said casing having top and bottom walls, the top wall having slots formed therein and perforating elements carried by the top wall and received within the slots; said perforating elements being so formed as to permit individual manipulation thereof. 7. A check protector, comprising a casing adapted to chamber a check, said casing having a cover with slots therein, and perforating elements freely inserted in the slots for disposition in relative arrangement for conjoint use. 8. A check protector, comprising a casing adapted to chamber a check, said casing having a cover with slots therein, and per-
- forating elements freely inserted in the slots for disposition in relative arrangement for conjoint use; said perforating elements being depressible through the slots. 9. A check protector, comprising a casing adapted to chamber a check, said casing having a cover with slots therein, and perforating elements freely inserted in the slots for disposition in relative arrangement for conjoint use; said slots including a portion in which the perforating elements are normally disposed, a portion in which they are disposed for use, and a further connecting portion. 10. A check protector, comprising a casing adapted to chamber a check, said casing having a cover with slots therein, and perforating elements freely inserted in the slots for disposition in relative arrangement for conjoint use; a pad being provided under the slotted portion of the cover.

In testimony whereof, I have signed my name to this specification in the presence of two subscribing witnesses.

EDWIN H. DRYER.
